UNITED STATES PATENT OFFICE

2,684,644

UNIT DOOR LATCH

George B. Dorey, Westmount, Quebec, Canada,
assignor to Enterprise Railway Equipment
Company, Chicago, Ill., a corporation of Illinois

Application August 25, 1949, Serial No. 112,226

4 Claims. (Cl. 105—308)

1

This invention relates, generally, to railway cars of the hopper type and it has particular relation to latching mechanisms for the hopper doors thereof.

Among the objects of this invention are: To construct a latching mechanism for the door of a hopper so that the force applied to move the latch bar into locking engagement with the cooperating shouldered element or hook on the hopper is also used to swing the door to the closed position; to position the hook so that it provides a minimum of interference with the flow of lading therewith; to arrange the latch bar which engages the hook so that it seals off the aperture in the door through which the hook projects; to locate the latch bar substantially entirely to one side of the hook; and to provide for wedging the door from the partly closed to the fully closed position.

Other objects of this invention will, in part, be obvious and in part appear hereinafter.

This invention is disclosed in the embodiment thereof shown in the accompanying drawings and it comprises the features of construction, combination of elements and arrangement of parts which will be exemplified in the construction hereinafter set forth and the scope of the application of which will be indicated in the appended claims.

For a more complete understanding of the nature and scope of this invention, reference can be had to the following detailed description, taken together with the accompanying drawings, in which:

Figure 1 is a detail sectional view taken generally along the line 1—1 of Figure 3 and showing a latch mechanism for the door of a hopper, the door being shown closed;

Figure 2 is a view similar to Figure 1 and showing the latch mechanism holding the door in the partly closed position;

Figure 3 is a view, in front elevation, of the door in the open position mounted along its upper edge on the hopper;

Figure 4 is a view showing the lower portion of the door in the fully closed position with the latching bar locked in this position;

Figure 5 is a view, similar to Figure 4, showing how the latching bar cooperates with the hook shaped element on the hopper to swing the door to the fully closed position;

Figure 6 is a view of a strap which is employed for pivoting the latching bar and the locking dog and providing a fulcrum for the operating bar; and

2

Figure 7 is a view, in side elevation, of the strap shown in Figure 6.

Referring now particularly to Figures 1 and 3 of the drawings, it will be observed that the reference character 10 designates a center sill of a conventional railway car having a side frame 11 spaced therefrom with a hopper 12 therebetween. The hopper 12 is formed by side walls 13 and 14, a top wall 15, and a floor 16 which slopes downwardly to an opening 17. Surrounding the opening 17 is a frame that is indicated, generally, at 20. It comprises a stirrup portion, shown generally at 21, which has frame sides 22 and 23 and a frame bottom 24 all of which have a T-shaped cross section as shown more clearly in Figure 1. The frame 20 is completed by a top frame member 25 from which hinge butts 26 projects. The hinge butts 26 carry hinge pins 27 which support hinge straps 28 at their upper ends. The hinge straps 28 are secured by rivets 29 to a door which is indicated, generally, at 30. The door 30 is generally pan shaped and it has a flange 31 around its edge which fits over the juxtaposed flat portions of the frame 20, as shown in Figure 1, so as to provide a tight seal therewith.

Mounted on the floor 16 is a shouldered or hook shaped element 34 which may be secured thereto by rivets 35. The element 34 has a shank portion 36 which projects through an opening 37, Figure 2, in the door 30 and also through a registering opening 38 in a beam member 39 which may be secured by rivets 40 to the lower edge of the door 30 and which extends along the same as shown in Figure 3. It will be observed that the beam member 39 is generally of Z-shape cross section intermediate its ends and that the intermediate plate portion 41, Figure 3, is positioned flat against the lower outer surface of the door 30. The upper flange of the Z-shaped cross section which is indicated at 42 extends outwardly and defines the upper edge of the opening 38. The lower flange 43 of the Z-shaped cross section underlies the flange 31 of the pan shaped door 30.

The shouldered or hook shaped element 34 which is mounted on the floor 16 has a nose portion 44, Figure 2, in which there is a notch 45 that opens downwardly. This construction provides a minimum of interference with the flow of lading past the shouldered or hook shaped element 34.

At its outer end the nose portion 44 has an inclined under surface 47 which is arranged to engage the upper edge 48 of a latching bar 49 for the purpose of automatically moving the same

to a position where it can fall into the notch 45 in a manner to be described.

As illustrated in Figure 3 of the drawings, the latching bar 49 is pivotally mounted intermediate its ends. For this purpose a boss 50, Figure 7, is provided on a strap 51 and formed integrally therewith. The strap 51 is secured in position on the door 30 by rivets 52 and 53. It will be understood that the rivet 52 extends through the intermediate plate portion 41 of the beam member 39 while the rivet 53 extends through a bracket 54 that extends upwardly from the beam member 39 and is formed integrally therewith.

As shown in Figure 1 the nose portion 44 of the hook shaped element 34 is provided with stepped faces 55 and 56 which are parallel to each other but are offset and are interconnected by an inclined wedging face 57. Similarly the latching bar 49 is provided with stepped faces 59 and 60 which are parallel to each other and which are interconnected by an inclined wedging face 61 as shown in Figure 2.

In Figure 1 it will be observed that the stepped faces 59 and 60 of the latching bar 49 are in mutual engagement with the corresponding stepped faces 55 and 56 when the door 30 is held in the fully closed position. If desired, in this position the inclined wedging faces 61 and 57 also can be in engagement to provide additional bearing surface between the hook shaped element 34 and the latching bar 49.

It is desirable that the opening 37 in the door 30 and the opening 38 in the beam member 39 be sealed off when the door 30 is closed so as to prevent the escape of lading therethrough. For this purpose the opening 38 is provided with a beading 62 therearound which constitutes an integral extension of the upper flange 42. The inner surface 63 of the latching bar 49 is arranged to sealingly engage this beading 62 and thus, when the door 30 is closed, the lower portion of the opening 38 in the beam member 39 is sealed off. It will be understood that the upper portion of this opening is sealed off by the portion of the hook shaped element 34 which engages the inner surface of the door 30.

With a view to having the latching bar 49 operate automatically when the door 30 is swung to the closed position, it is pivoted intermediate its end so that the left hand portion 66, Figure 3, is longer than the right hand portion 67. Since the left hand portion 66 is of greater weight than the right hand portion 67, the latching bar 49 is biased to rock in a counterclockwise direction and, when the door 30 is open, it is held in substantially a horizontal position by engagement with the lower ends 42' of the upper flange 42 which constitutes a part of the beam member 39.

The left hand portion 66 of the latching bar 49 is provided with a projection 68 for receiving an operating bar that is indicated at 69 by broken lines in Figure 5. The operating bar 69 is arranged to engage the upper edge of the projection 68 and to bear against the underside of a fulcrum boss 70 which is formed integrally with the strap 51 as shown more clearly in Figure 7.

As illustrated more clearly in Figure 1 of the drawings, the latching bar 49 is pivoted to swing parallel to the front side of the door 30 in a plane which is offset from the plane containing the hinge pins 27 or the hinge axis of the door 30. The distance between the plane of the latching bar 49 and the plane of the hinge axis of the door 30 is indicated at 71. Now when the operating bar 69 is positioned as shown in Figure 5 under-

neath the fulcrum boss 70 and above the projection 68 to swing the latching bar 49 to the fully latched position, the force exerted thereby also creates a moment about the hinge axis of the door 30 and thus tends to swing it to the closed position in addition to the force exerted thereon by the movement of the upper right hand corner 72 over the inclined wedging face 57.

The latching bar 49 is held in the closed position by a locking dog 73 that may be rockably mounted on a boss 74, Figure 7, through which the rivet 53 projects. A lug 75, formed integrally with the locking dog 73, is provided for receiving one end of the operating bar 69 to pry it out of its locked position as shown in Figure 4.

In describing the operation of the latching mechanism disclosed herein, it will be assumed first that the door 30 is closed and that the locking dog 73 occupies the locked position shown in Figure 4. The operating bar 69 is inserted underneath the lug 75 and above the projection 68 on the latching bar 49. The locking dog 75 is pried out of the locked position and is swung to the position shown in Figure 5 where it is held by engagement between the lug 75 and the strap 51. Next the operating bar 69 is placed with its fulcrum end on top of the fulcrum boss 70 and the intermediate portion extending underneath the projection 68. The application of force to the outer end of the operating bar 69 causes the latching bar 49 to be rocked in a clockwise direction and out of engagement with the hook shaped element 34. The lading bearing against the door 30 and the weight of the door 30 itself cause it to swing to the open position about the hinge axis through the hinge pins 27. Because of the down-turned position of the nose portion 44 there is a minimum of interference to the flow of lading past the hook shaped element 34.

When the door 30 is to be closed, it is swung toward the position shown in Figure 2 where the face 60 engages the face 55 of the nose portion 44. This is done automatically by the inclined under surface 41 bearing against the corner edge 48 of the latching bar 49 and moving it downwardly as the door 30 is swung toward the closed position. Now the operating bar 69 is positioned as shown in Figure 5 with the fulcrum end underneath the fulcrum boss 70 and the intermediate portion of the bar above the projection 68. Force applied to the outer end of the operating bar 69 then causes the latching bar 49 to rock in a counter-clockwise direction. This moves the face 60 on the latching bar 49 over the inclined wedging face 51 on the nose portion 44 until, in the fully closed position, the face 60 bears against the face 56 while the face 59 bears against the face 55 as shown in Figure 1. During the movement over the inclined wedging face 51, the door 30 is wedged to the fully closed position. It is assisted in this movement by the application of force to the outer end of the operating bar 69 which acts at a distance from the hinge axis of the door 30 as indicated at 71.

Since certain changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. In a railway car having a hopper with a discharge opening and a door hinged along one side of said opening for closing the same, in combina-

tion, latching means adjacent the swinging edge of said door, said latching means including a shouldered hook-shaped latching element stationarily carried by said hopper intermediate its ends with the hook opening downwardly and a latching bar pivotally mounted on said door for engaging with the shoulder of said latching element, said latching bar extending substantially parallel to the hinge axis of said door and pivoted intermediate its ends so that one end swings toward said hinge axis to engage with said shoulder, said latching bar being spaced outwardly from a plane through said hinge axis and movable in a plane parallel to the plane of said door, said shouldered latching element having a wedging face engageable by said latching bar whereby force applied to the other end of said latching bar in a direction away from said hinge axis to move said latching bar to the latched position exerts a pull on said door about its hinge axis in a direction to close the same.

2. In a railway car having a hopper with a discharge opening and a door hinged along one side of said opening for closing the same, in combination, latching means adjacent the swinging edge of said door, said latching means including a shouldered hook-shaped latching element stationarily carried by said hopper intermediate its ends with the hook opening downwardly and a latching bar pivotally mounted on said door for engaging with the shoulder of said latching element, said latching bar extending substantially parallel to the hinge axis of said door and pivoted intermediate its ends so that one end swings toward said hinge axis to engage with said shoulder, said latching bar being spaced outwardly from a plane through said hinge axis and movable in a plane parallel to the plane of said door, said latch bar having a wedging face for engagement with said latching element and being movable in a plane spaced from said hinge axis of said door whereby on application of force to the other end of said latch bar in a direction away from said hinge axis to move said latching bar into wedging relation with said latching element to close said door a turning moment is exerted on said door about its hinge axis in a direction to close the same.

3. In a railway car having a hopper with a discharge opening and a door hinged along one side of said opening for closing the same, in combination, latching means for retaining said door closed including interengaging members carried by said door and hopper, respectively, said means carried by said door including a latching bar pivoted intermediate its ends on said door to swing parallel thereto with one end swinging toward the hinge axis of said door and the other end swinging away therefrom, said latching bar being spaced outwardly from a plane through said hinge axis, said means carried by said hopper including a hook-shaped member stationarily mounted on said hopper intermediate its sides

with the hook opening downwardly and having a shoulder adapted to engage with said one end of said latching bar, said one end of said bar and said shoulder each having stepped engaging faces connected by an inclined face for maintaining said door in either a partly closed or a fully closed position, the inner engaging face of said one end of said bar and the outer engaging face of said shoulder being arranged to mutually engage to hold said door partly closed and on application of force to said other end of said bar in a direction away from said hinge axis to move along the inclined face of the other to mutually engage both faces of each in the fully closed position of said door and to exert a turning moment on said door about said hinge axis in a direction tending to close the same.

4. In a railway car having a hopper with a discharge opening and a door hinged along one side of said opening for closing the same, in combination, latching means adjacent the swinging edge of said door, said latching means including shouldered hook-shaped keeper means stationarily mounted on said hopper intermediate its sides with the hook opening downwardly and a latch bar pivotally mounted intermediate its ends on said door having one end swingable towards the hinge axis of said door for engagement with said keeper means, said latching bar being spaced outwardly from a plane through said hinge axis and movable in a plane parallel to the plane of said door, said keeper means and said one end of said latch bar having cooperating stepped shoulders with an intervening inclined surface therebetween, one engaging pair of said stepped shoulders being adapted to bear the weight of the door in partly closed position; said latch bar being arranged to swing along the face of the keeper shoulder on application of force to the other end of said latch bar in a direction away from said hinge axis for moving the door from partly closed to fully closed position, said latch bar being spaced outwardly from the hinge axis of the door whereby upon movement of the latch bar in wedging relation with said keeper means by said force a turning moment is exerted on said door about its hinge axis to urge the same towards closed position simultaneously with the wedging action between said latch bar and keeper means.
